UNITED STATES PATENT OFFICE

2,230,170

CIRCUIT CLOSER FOR BURGLAR ALARMS

Reger Q. Traweek, Jr., Houston, Tex.

Application August 9, 1938, Serial No. 223,967

1 Claim. (Cl. 200—52)

This invention relates to burglar alarms, and its general object is to provide an alarm for use with windows, doors and other closures including transparent panes, such as glass or the like, as

5 my invention consists essentially of a pane of glass having spaced conductor wires embedded therein and insulated from each other by the glass but in circuit with alarm means and a suitable source of current, so that in the event the 10 glass is broken the wires contact and close the circuit to the alarm means.

A further object is to provide a burglar alarm including switch means that is rendered active to close the circuit, immediately upon contact 15 of the glass embedded conductors, and the circuit remains closed even though the conductors become separated.

Another object is to provide a burglar alarm of the character set forth that includes conductor 20 wires embedded in the glass in a manner, so that regardless of where the glass is broken, the wires must necessarily contact to close the circuit for the purpose referred to.

A still further object is to provide a burglar 25 alarm that is simple in construction, inexpensive to manufacture, easy to install, and extremely efficient in operation, use and service.

This invention also consists in certain other 30 features of construction and in the combination and arrangement of the several parts, to be hereinafter fully described, illustrated in the accompanying drawing and specifically pointed out in the appended claim.

In describing the invention in detail, reference 35 will be had to the accompanying drawing wherein like characters denote like or corresponding parts throughout the several views, and in which:

Figure 1 is a front view of my burglar alarm glass.

40 Figure 2 is a sectional view taken approximately on line 2—2 of Figure 1, looking in the direction of the arrows.

Figure 3 is a diagrammatic view of the circuit for the alarm.

45 Figure 4 is a detail view illustrating the peculiar arrangement of the conductor wires within the glass.

Referring to the drawing in detail, the reference numeral 1 indicates a pane of glass, or other 50 suitable transparent means, and while the pane is shown as being square, it will of course be understood that it can be made in any shape without departing from the spirit of the invention. The pane is mounted in a channel frame 2 that 55 is preferably made from rubber or other material

suitable for the purpose, and it will be noted as best shown in Figure 1 that one corner of the frame is provided with an opening therethrough for the passage of conductors 3 and 4.

The conductors 3 and 4 are embedded within 5 the pane 1 and extend about the marginal edge thereof, as well as insulated from each other by the glass, in that the conductors are spaced from each other, as will be apparent. The conductors terminate at one of their ends within the pane 10 and are arranged in a manner to provide parallel portions for each conductor, and the parallel portions of the conductor 3 and which are indicated by the reference numerals 5 and 6 have bridging the same and connected thereto conductors 7 15 arranged in zigzag row formation, while the parallel portions 8 and 9 of the conductor 4 also have bridging the same and connected thereto conductors 10 arranged in zigzag row formation, but of course are spaced and insulated from the 20 conductor 7, due to the arrangement of the respective portions of the conductors 3 and 4 with respect to each other, and as will be apparent upon inspection of Figure 2. It will be further noted as best shown in Figure 3 that the conductors 7 and 10 are disposed at right angles to each other, and it is believed that it will be obvious that in the event the pane is broken at any place in its area, the conductors 7 and 10 25 will contact with each other, for a purpose which 30 will be later described.

While the portions of the conductors 3 and 4 that are arranged within the pane are bare or in other words are not covered by insulating covering material, the portions of the conductors 3 35 and 4 that extend through the opening in the frame 2, as well as other exterior portions thereof, are covered by suitable insulating material. The conductor 3 extends to a main switch 11 that likewise has a conductor 12 connected thereto 40 that in turn is connected to a suitable source of current, while the conductor 4 is connected to suitable alarm means, such as a bell 13, as shown in Figure 3, and the bell is grounded by a conductor 14 which has one end connected to the 45 bell conductor 15. While the alarm means is shown as being a bell, it will be obvious that it can be visual means, or other suitable audible means.

From the above description and disclosure in 50 the drawing, it will be obvious that when the main switch 11 is closed, and any portion of the glass embedded conductors should become disposed in contact, upon breaking of the glass as 55

will be apparent, the circuit will be closed to the alarm means or bell 13.

While the circuit will be closed to the alarm means, in the event that the embedded conductors should become disposed in contacting engagement, the circuit will be open, should the conductors become separated, and in order to eliminate that disadvantageous feature, I employ switch means in the above circuit which includes 5 a base 16 having mounted thereon a relay including a magnet 17 and an armature arm 18, the relay being in circuit with the conductor 4 by a conductor 19 and with the alarm means by the conductor 15. The relay is primarily designed 10 for operating a switch that includes an upright 20 mounted on and rising from the base 16, with spring contact fingers 21 arranged in pairs thereon, for receiving contact members 22 carried by an arm 23 pivotally secured to the base 16. The 15 armature arm 18 is likewise pivotally secured to the base and pivotally mounted between the ends of the armature arm 18 is one end of a lever 24 that has its opposite end engaging the switch arm 23, for moving the contact members 22 between 20 the fingers 21, for the latter to set up a gripping engagement therewith to hold the switch closed, and the circuit accordingly, when the relay is energized, as will be apparent. One pair of the 25 contact fingers 21 is connected to the conductor 3, by a conductor 25, while the other pair is connected to the conductor 4 by a conductor 26.

It is believed that the operation of the switch means will be apparent but it might be mentioned that by use of the switch means, that in the event 30 the glass embedded conductors should become separated, the alarm means will be continuously operated, and such as brought about by the relay being energized, for moving the switch arm 23 to closed position, through the instrumentality of

the lever 24. In order to open the circuit, the switch arm 23 must be manually moved to open position. I have also illustrated guiding and supporting means 27 for the lever 24 and which preferably includes a roller 28 having the lever 24 5 mounted thereon, as clearly shown in Figure 3.

It is thought from the foregoing description that the advantages and novel features of the invention will be readily apparent.

It is to be understood that changes may be 10 made in the construction and in the combination and arrangement of the several parts, provided that such changes fall within the scope of the appended claim.

What I claim is:

In an electric burglar alarm, a pane of glass 15 for windows, doors and the like, a pair of spaced conductors embedded within the pane to follow the marginal edge thereof in close proximity thereto and arranged to provide parallel portions, said conductors extending from said pane through one corner thereof and having one of their ends terminating within said pane, conductors connected to and bridging the parallel portions of each of the first conductors and arranged in row formation, the rows being in spaced planes and disposed at right angles to each other, the conductors of each row being disposed in zig-zag formation and in equi-distantly spaced relation to each other, certain of the zigzag portions 20 of the conductors of one row being disposed parallel with and in close proximity to certain of the zigzag portions of the conductors of the other row, a channel frame of insulating material with the pane mounted in the channel thereof, and 25 said frame having an opening in one of its corners for the passage of the first conductors therethrough for connection in circuit with an alarm. 30

ROGER Q. TRAWECK, JR.
